UNITED STATES PATENT OFFICE.

JOHN H. CROWELL, OF VINEYARD HAVEN, MASSACHUSETTS.

PRESS.

1,076,023.

Specification of Letters Patent.

Patented Oct. 21, 1913.

Application filed March 29, 1912. Serial No. 687,206.

To all whom it may concern:

Be it known that I, JOHN H. CROWELL, a citizen of the United States, residing at Vineyard Haven, in the county of Dukes 5 and State of Massachusetts, have invented a new and useful Press, of which the following is a specification.

The purpose of my invention is to provide a press readily convertible into and 10 usable as a foot press, a screw press, or a combined foot and screw press.

To these ends my invention consists in the new and novel construction combination and arrangement of parts hereinafter described, 15 and shown in the accompanying drawings, in which:

Figure 1 is a front elevation of a press embodying my invention. Figs. 2, 3 and 4 are side elevations, partly in section, of the 20 same.

Like reference letters and numerals indicate like parts in all the views.

In the drawings, A represents the table of my press, supported upon legs or standards 25 A¹ and in turn supporting a frame A², all of the well known construction. A screw s is arranged and adapted to operate vertically through the upper cross member of the frame A², and is provided with the common operating handle s¹ and counterweight s². Said screw is threaded to engage with a nut 1, tapped to receive it, and arranged for vertical sliding movement in said frame in slide-ways formed in the uprights thereof, 30 as actuated by the screw s, or otherwise as hereinafter described. Said nut 1 is provided with a notch or recess 2 arranged and adapted to be engaged by an adjustable dog 3 mounted in said frame for horizontal reciprocating movement and provided with an 35 adjusting screw 4 tapped into the upright of said frame. Said dog serves to hold the said nut 1 stationary in said frame when the press is to be used as a screw press, operated 40 by the handle s¹. A set-screw 5 tapped through the front of the nut 1 serves, when in contact with the screw s, to lock said nut and screw together for united movement when the dog 3 is disengaged from the notch 45 2, in which case the said nut slides in the guide-ways above mentioned, carrying with it said screw s in vertical reciprocating movement when the press is operated as a foot press, by the treadle hereinafter described. Said screw s extends through beyond and below the nut 1, and a follower 50 55

is secured to its lower end and, spaced a distance below said nut, is arranged and adapted for reciprocating movement vertically in said guide-ways. I pivotally mount in said frame a treadle 7 arranged with its upper arm extending into and through the space between the nut 1 and the follower 6, and provide the outer end of said arm with a perforation arranged and adapted for the 60 operation therethrough of said screw s, or for the operation of said treadle without contact with said screw. A set-screw 7¹ tapped through the front end of the upper arm of the treadle 7 serves, by its engagement with a groove or score s³ in the lower portion of said screw s, to unite said screw and treadle for conjoint action.

In the practical operation of my invention, when the press is to be used as a screw 75 press operated by the counterbalanced handle s¹ the set screw 5 and set screw 7¹ are withdrawn from contact with the screw s, the dog 3 is by operation of the adjusting screw 4 made to engage the notch 2 in the nut 1, 80 thereby holding the nut stationary in the upper part of the guideways, and allowing the screw s to operate freely therethrough, as actuated by the handle s¹ in the same manner as the well known screw press is 85 operated. The screw s in this case having free movement in the perforation in the upper outer end of the treadle arm without disturbing or moving the treadle 7 (Fig. 3).

When it is desired to use the press as a 90 foot press operated by the treadle 7, the dog 3 is withdrawn from engagement with the notch 2 and the set screw 7¹ is withdrawn from notch s³, and the set screw 5 is turned into contact with the screw s, thereby locking 95 said screw and the nut 1 together for united movement. Operation of the treadle 7 in the usual way then imparts to the nut, 1, screw s and follower 6 united vertical movement in both directions (Fig. 2).

When it is desired to use the press as a 100 combined foot and screw press, or in other words, when it is desirable to obtain in a single operation the benefit of both the treadle and screw movements, the dog 3 105 is made to engage the notch 2, thereby locking the nut 1 immovably in the frame, and the set screw 5 is withdrawn and held out of contact with the screw s, and the set screw 7¹ caused to engage the notch s³ thereby uniting the screw s and treadle 7 for 110 conjoint action. Operation of the treadle 7

in the usual way causes the follower to move vertically downward and also causes the screw s to revolve and move downward through the nut 1 thereby adding the force 5 of the blow of the counterweight s^2 to the force of the blow of the follower 6. In this arrangement of the parts the press may be operated by the handle s^1 , if desired, instead of by the treadle 7, with the same beneficial 10 result and effect (Fig. 4).

It is to be understood that wherever in this specification or in the claims I refer to the uprights and to the cross member connecting their upper ends, I mean to include 15 that form of construction in which the upright guideway carrying member and the upper cross member are integral.

It will be noted as a novel and important 20 feature of my invention shown and described hereinbefore, that whether operated by the treadle 7 or by the counterweighted handle s^1 , the counterweight s^2 will be caused to swing with velocity within a predetermined arc, upon the screw s as a pivot, and that 25 its impetus will be suddenly checked at the end of such movement and will thereby materially and importantly add to the force of the final blow of the follower-carried-die upon the anvil usually located upon the table 30 A. In other words by my invention I am enabled to utilize to the fullest extent the benefit and advantage of the impetus and weight of both the counterweight s^2 and follower 6, to make more effective the operation 35 of the press.

I claim:

1. In a press having a table, uprights carried on said table and provided with guideways, and also with a perforated cross 40 member connecting the upper ends of said uprights, the combination with said parts of a follower slidably fitted in said guideways, an internally threaded nut slidably fitted in said guideways and spaced a distance above said follower, a screw extending 45 through said perforated cross member, and

through said nut and connecting said nut and follower, means for locking said nut, at will, immovably in the upper portion of said guideways, and other means for actuating said screw through said nut and cross member to depress and raise said follower in the guideways. 50

2. In a press having a table, uprights carried on said table and provided with guideways, and also with a perforated upper cross member connecting said uprights, the combination with said parts of a follower slidably fitted in said guideways, an internally threaded nut slidably fitted in the upper part of said guideways and spaced a distance above said follower, a treadle pivotally mounted in said uprights and having its upper arm perforated and extending into the space between said nut and follower, a screw arranged for operation through said perforated cross member, internally threaded nut and perforated treadle arm, and connecting said nut and follower for united action, and means for connecting said screw 65 to said treadle arm, and other means for binding said slidable nut upon said screw. 70

3. In a press having uprights provided with guideways and connected at the upper ends by a perforated cross member, the combination 75 with said parts of an internally threaded nut slidably fitted in said guideways, a follower slidably fitted in said guideways and spaced a distance below said nut, a treadle pivotally mounted in said uprights and provided with a perforated upper arm extending into the space between said nut and follower, an externally threaded screw provided with a counterweighted operating handle, and arranged for operation through 80 said cross member, nut and perforated treadle arm, and connecting said nut and follower for united action. 85

JOHN H. CROWELL.
